ATTORNEY.

UNITED STATES PATENT OFFICE.

NELS P. TANGWALL, OF DULUTH, MINNESOTA.

PORTABLE SHEARS.

1,342,473.

Specification of Letters Patent. Patented June 8, 1920.

Application filed September 6, 1919. Serial No. 322,046.

To all whom it may concern:

Be it known that I, NELS P. TANGWALL, citizen of the United States, residing at Duluth, in the county of St. Louis and State 5 of Minnesota, have invented certain new and useful Improvements in Portable Shears, of which the following is a specification, reference being had therein to the accompanying drawing.

10 This invention relates to certain improvements in shears and has special reference to portable hand shears for cutting metal.

The principal object is to provide a convenient form of such shears for shop use 15 and one having supporting means which may be employed for other purposes if desired.

Other objects and advantages of the invention will appear in the further description thereof.

20 Referring to the accompanying drawings forming part of this application and in which like reference characters indicate like parts:

25 Figure 1 is a side elevation of one of my improved shears.

Fig. 2 is a sectional view taken on the line 2—2, Fig. 1, showing the holding means in elevation.

30 Fig. 3 is a section on the line 3—3, Fig. 2, and

Fig. 4 is an elevation of a fragmental portion of the body of the shears.

1 represents the body portion of the shears 35 the upper end of which terminates in the extended cutting jaw 2 upon one side and an extension 3 upon the opposite side, in which latter is formed a plurality of different sized holes 4 in which round iron or 40 wire may be cut. The lower part of the body portion 1 has an extension 5 thereupon and formed at right-angles thereto, this extension being primarily for engagement with the table or bench upon which the 45 shears are placed.

The body portion 1 has a vertically disposed channel or recess formed therein, the bottom of which is serrated or toothed as at 6 said channel being formed through the 50 base of the extension or jaw 5 and adapted to receive the complementally toothed shank 7 which forms a longitudinally disposed extension of the body 1. The lower end of the extension 7 is turned at right angles thereto forming a support 8 for the manually operative screw 9, the upper end of

which carries the jaw 10 which forms the lowermost member of the clamping means for supporting the shears upon a table, bench or the like. The lower body portion 60 of the extension 7 is centrally slotted as at 11 providing a guide for the inner end of the jaw 10 which extends therein and prevents the latter from turning with the screw 9, the extreme inner end of said jaw being 65 beyond the shank 7 being reduced and provided with a suitable washer and nut as shown at 12. The shank 7 is held in any predetermined position in the channel by a suitable bolt 19 and wedge 20 there being 70 a slot 21 in the center of the channel to accommodate such adjustment.

In having a second jaw corresponding in size and extent to the jaw 5 and made reciprocably carried upon the screw 9, I have 75 provided a convenient portable vise which may be of considerable service when the shears are not being used.

At 13 I have shown pivotally mounted the upper member or jaw 14 of the shears 80 which co-acts in the process of cutting with the jaw 2 and the holes 4 alternately, said member 14 being provided with a suitable rigid handle 15 for manipulating same.

As a gage for cutting either rods or plate 85 a given predetermined length, I have formed a laterally projecting hub 16 upon the lower jaw member of the shears and through which hub is longitudinally adjustably mounted a rod 17 carrying an arm 18 upon one end thereof and which arm may 90 be placed any desired distance from the shears within the limits of the length of the rod 17 it being possible to swing the arm 18 either opposite any one of the holes 4 or 95 opposite the cutting shears to act as such gage.

From the foregoing it is evident that I have devised a convenient combination tool for the purpose intended and while I have 100 shown one specific embodiment of same it is evident that various modifications within the scope of the claims may be resorted to without departing from the spirit of the invention.

Having thus described my invention what I claim as new and desire to secure by Letters Patent is:

1. The combination with a manually operated tool of the character described of a 110 support therefor comprising a body portion, an extension longitudinally adjustably car-

ried by said body portion, a laterally extending fixed jaw carried by the body portion, a manually operated screw carried in the lower end of the extension and a second jaw carried upon the screw, and slidable within the extension for coöperative action with the fixed jaw.

2. A tool support of the character described comprising an upright body portion 10 having a jaw extending laterally therefrom, a recessed channel within the face of the body portion from which the jaw extends and passing through the base of the jaw, an extension slidably mounted within the 15 channel and carrying a vertically adjustable screw in its lowermost angular end, and a second jaw slidable within the extension and carried upon the end of the screw for co-action with the fixed jaw.
- 20 3. A clamping and holding device of the character described comprising in combina-

tion a principal slotted body portion having an angular jaw formed integral therewith, a second slotted body portion slidable through the jaw of the principal body portion and having a fixed jaw at the outer termination thereof, said fixed jaw being parallel and in line with the first mentioned jaw, a third jaw slidably carried upon the second body portion and reciprocable intermediate of the first and second jaws, means carried by the latter for such reciprocation and means for holding the two body portions rigidly united, substantially as described. 25 30 35

In testimony whereof I hereunto affix my signature in the presence of two witnesses.

NELS P. TANGWALL.
